UNITED STATES PATENT OFFICE.

GEORGE H. GILMAN, OF BELMONT, MASSACHUSETTS.

DRILLING MACHINE.

Application filed July 12, 1921. Serial No. 484,072.

My invention relates to drilling machines and more particularly but not exclusively to a hammer rock drill.

The invention will be best understood 5 from the following description when read in the light of the accompanying drawings of a specific embodiment of the invention selected for illustrative purposes, while the scope of the invention will be more particularly pointed out in the appended claims.

In the drawings:

Fig. 1 is a central longitudinal section of a hammer rock drill embodying my invention;

Fig. 2 is a central longitudinal section on a plane at right angles to that of Fig. 1;

Figs. 3, 4 and 5 respectively are sections on the lines 3—3, 4—4 and 5—5 of Fig. 1;

Figs. 6, 7 and 8 are diagrams illustrating 20 the operation of the gear shifting mechanism and its controlling valve; and

Fig. 9 is a section on the line 9—9 of Fig. 1, with the valve moved to the position illustrated by Fig. 7.

Referring to the drawings, I have shown 25 a cylinder or casing for housing the operative parts of the machine. Herein the cylinder comprises first, a front head or chuck casing 1 which provides both a rotatable support for the sectional chuck 3 and a casing for the gearing hereinafter described; second, a main cylinder portion 5 which is provided with a bore for receiving the large head 7 of the piston; third, a block 9 which 30 supports a rearward cylinder section 11 providing a bore for receiving the shank 13 of the piston; fourth, a motor casing 15; and fifth, a rear cylinder head 17. These parts of the cylinder or casing are shown as held 35 in assembled relation by means of through-bolts 19 of which I have shown four, each extending from the rear cylinder head to the flange 21 of the chuck casing.

The drill steel 23 herein is provided with 40 lugs 25, received in recesses 27 in the chuck, which construction in a known manner permits insertion of the drill steel and retains it when inserted, and at the same time permits a slight longitudinal movement of the 45 steel relative the chuck and constrains it to rotate therewith. For striking the drill steel, the hammer piston is shown as provided with a hammer bar 29, which fits the front head 31 of the main cylinder portion 50 in a fluid-tight manner and is adapted to strike the rearward end of the steel at the

end of the forward stroke of the hammer piston.

Herein motive fluid is supplied the machine through a hose connection 33, which 60 conducts the motive fluid to the casing of a throttle valve 35 adapted to supply motive fluid or to interrupt such supply to the intake passage 37 for the hammer. For distributing the supply, the bore of the rearward cylinder member 11 is shown as provided near its forward end with an internal annular groove 39 and with this groove the passage 37 communicates. Leading rearwardly from the annular groove is a 65 longitudinal groove 41 formed in the interior wall of the bore of the cylinder member 11, while in the same plane as the rearward portion of the groove 41 and diametrically opposite thereto is the port 43 of 70 the passage 45 leading to the forward end of the larger cylinder bore. Further, the shank is shown as provided with a reduced diameter portion 47, while opening into the intermediate portion of the larger bore of 75 the cylinder is an exhaust passage 49 adapted to be alternately placed in communication with the cylinder chambers at opposite sides of the head 7 by the reciprocations of the latter.

In the position of the parts shown by Fig. 1, motive fluid is conducted from the supply passage 37 through the annular groove 39, the groove 41, the port 43 and passage 45 to supply live motive fluid to the cylinder chamber forwardly of the head 7 and as at this time the cylinder chamber at the rear of the head is placed in communication with the atmosphere by the passage 49, the piston will move rearwardly. Rearward movement of the piston closes the port 43 and near the end of the rearward stroke places the groove 39 in communication with the cylinder chamber at the rear of the head 7 by means of the reduced diameter portion 47 of the shank. After the piston opens the passage 49 to the cylinder chamber forwardly of the head, the air which has been admitted thereto during the rearward stroke is exhausted to the atmosphere. Under these conditions the piston will move forwardly, aided by the fluid acting on the rearward end of the shank in a manner hereinafter to be described.

For rotating the chuck I have shown a 105 rotary engine, which engine herein comprises a centrally located toothed rotor 51

and the toothed rotary abutments 53 in mesh with the rotor. The rotor is journalled on the exterior of the reduced diameter portion 55 of the rearward cylinder section 11, while 5 the abutments are keyed to shafts 57. The motor casing 15 is formed to fit the periphery of the rotor and abutments except at the point adjacent their intersection, where are located the intake passages 59 and opposite 10 site these the exhaust passages 61.

As illustrated the rearward cylinder section 11 is provided with a cylindrical flange 63 and the rear cylinder head with a cylindrical flange 65 over which flanges fits the 15 central bore of the motor casing, the smaller bores of the motor casing fitting over the flanges 67 of the bearing blocks 69 supporting the rearward end of the shafts 57. In this manner is formed a casing for the 20 rotary engine.

In the contacting surfaces of the block 9 and the rearward cylinder section 11 are shown adjacent interior and exterior annular grooves which provide an annular 25 chamber 71 with which the exhaust passages 61 of the motor communicate and which is placed in communication with the atmosphere by means of the passage 73. The flange 65 hereinbefore referred to is shown 30 as made integral with the sleeve 75, over which sleeve is placed the body portion of the rear cylinder head 17 and which sleeve is carried by the rearward extremity of the section 11. In the face of the flange 65 35 abutting the body portion is formed an annular groove 77, with which the intake passages 59 of the motor communicate. Motive fluid is supplied the groove by way of a suitable valve 79 arranged to throttle or 40 completely interrupt the supply.

For supplying the chuck rotating motor with motive fluid, I herein provide a suitable conduit means leading both from the motive fluid supply connection and from 45 the smaller cylinder bore to the motor throttle. In the submitted embodiment of my invention, this conduit means comprises a passage indicated in its entirety by 81 and which opens into the rear cylinder chamber 50 and is in permanent communication with the motive fluid supply by way of a communicating slot 83 formed in the valve sleeve 85, other portions of this conduit means being provided by the rear cylinder 55 chamber and the passage indicated in its entirety by 87 and leading from the rear cylinder chamber to the throttle valve 79. The conduit 81 provides a supply of motive fluid for the rear cylinder chamber and the 60 motor during the forward stroke of the piston. During the rearward stroke, the motive fluid admitted to the rear cylinder chamber through the conduit 81 and the groove 41 is compressed, which cushions the 65 hammer and increases the rotative effort

of the motor. Any suitable means for preventing the return of motive fluid from the rear cylinder chamber to the source during the rearward stroke may be provided. In the submitted embodiment of my invention, 70 such a means takes the form of the inwardly opening check valve 89 constructed to be operated by fluid in the manner usual with such valves and provided with the spring 90 to insure its seating. It will be noted 75 that in this manner a compressor is provided of which compressor the conduit 81 is the intake and the conduit 87 the outlet, and by means of which intake and outlet live motive fluid from the source of supply 80 is compressed to augment the pressure of the motive fluid.

As illustrated, on the forward end of each shaft 57 are oppositely arranged eccentrics 91 and on the corresponding eccentrics of 85 each shaft are carried the internal toothed yokes 93, which are adapted to surround and mesh with the exteriorly toothed portion 94 of the shiftable sleeve 95 splined to the chuck by means of cooperating tongues 97 and grooves 99. When the motor is in operation, the gear toothed portion of the particular yoke 93 in mesh with the sleeve is caused to roll around the gear toothed portion of the sleeve, which rotates the sleeve at a speed proportional to the difference in the number of teeth on that yoke and on the sleeve. One of the yokes is formed with a slightly different number of teeth than the other, in order that the torque impressed on the drill steel or its speed 90 may be varied by shifting the gear toothed portion of the sleeve from one yoke to the other. The space between the yokes is made of sufficient width to enable the gear toothed 95 portion of the sleeve to be placed intermediate the yokes, under which condition the chuck is disconnected from the motor. 100

For shifting the sleeve 95, the forward end thereof is shown as provided with an annular groove 101 which receives the lower end of the shipper bar 103, so that movement of the bar will cause corresponding movement of the sleeve. Herein, the mechanism for operating the shipper bar is carried by the chuck casing and comprises both a manually and a fluid operative means. The manually operative means as shown comprises a rod 105, bolted to the shipper bar and provided with a handle member 107 carrying the spring-pressed pin 109 adapted to engage recesses 111 formed in the surface of the chuck exteriorly of the portion 113 of the chuck casing which houses the shipper bar and gearing. The rod 105 is supported by the walls of an opening 114 which it fits and is held in adjusted position by engagement of the pins with the recess 111. 115

Herein, for operating the shipper bar by 120

fluid pressure, the upper end of the bar is attached to a piston rod 115 which in conjunction with the rod 105 acts to guide the bar and which is formed integrally with the 5 piston 117. This piston is reciprocably mounted in a sleeve 119 fitted in the bore 121 formed in the enlarged portion 123 of the chuck casing. As illustrated by Fig. 1, the sleeve terminates at an intermediate 10 portion of the bore 121 in order to provide a forward cylinder portion of a diameter larger than that provided by the sleeve and is provided with a flange 125 which holds it in position when the machine is assembled. 15 In the forward portion of the bore is the annular piston 127 which in a fluid-tight manner fits both the rod 115 and the cylindrical surface of the bore 121.

Rearwardly of the sleeve 119 I herein 20 provide a tapered bore 128 for receiving the throttle valve 129. As illustrated by Fig. 9, the throttle valve is of the turning plug type, being held to its seat by a spring 130 and having a stem 131 to which the valve 25 handle 132 is secured. For supplying the throttle valve with motive fluid I provide a conduit 133 leading rearwardly to the casing of the throttle valve 35 and communicating with the motive fluid supply by 30 means of an arcual groove 135 formed around the valve casing. In the same plane as the valve end of the passage 133 and leading from the bore 129 is a passage 137 communicating with the rearward end of 35 the cylinder for the piston 117, a passage 139 communicating with the forward end of the cylinder for the piston 127 and a passage 141 communicating with the adjacent ends of the two cylinders. The valve 40 is provided with a live air slot 143 with which communicates the radial passage 145 and with the latter communicates an exterior arcuate groove 147, the slot, passage and groove all being in the same plane with 45 the passages 137, 139, 141 and the conduit 133. Formed on the exterior surface of the valve is a longitudinal exhaust groove 149 and a wider longitudinal exhaust groove 151, while interiorly of the casing for the 50 valve is formed an annular groove 159 in permanent communication with the atmosphere through a port 161. The longitudinal exhaust grooves 149 and 151 have one end in the plane of the passages leading to the 55 cylinders and the other in the plane of the groove 159 so that when the exhaust grooves are in communication with the passages leading to the cylinders, the latter will be placed in communication with the atmosphere. 60

The gear shifting mechanism is shown in its neutral position in Fig. 6, under which conditions both yokes are disconnected from the sleeve 95. In this position of parts, motive fluid is supplied both the passages 137

and 139 leading to the cylinder ends most remote, while the passage 141 is connected to the atmosphere by way of the groove 151, which in this position of the valve communicates with said passage. This causes 70 both pistons to approach each other and be held at adjacent ends of their respective cylinders. When the valve is moved from the neutral position to the position illustrated by Fig. 7, motive fluid is exhausted through 75 the passages 139 and 141 and is supplied to the passage 137, which causes both pistons to move forwardly the full distance permitted by the construction and places the sleeve 95 in mesh with the forwardly located yoke. 80 When the valve is moved from the neutral position to that illustrated by Fig. 1, motive fluid is exhausted from the rearward end of the smaller cylinder and supplied to its opposite end, which causes the pistons 85 to assume the positions illustrated by the figure and the sleeve 95 to be placed in mesh with the rearwardly located yoke.

For permitting manual operation of the gear shifting apparatus the valve casing is 90 shown as provided with a longitudinal groove 163 formed in its interior surface and communicating at one end with the annular groove 159 while at its other end it terminates in the plane of the passages leading to the cylinder ends. Movement of the valve in the position illustrated by Fig. 8 closes off the intake passage 133 and connects all of the passages leading to the cylinder ends to each other and to the atmosphere 100 by way of the valve passages 143, 145, grooves 163, 159 and passage 161.

It will be observed that the percussive and chuck rotating motors herein described are of the type wherein the motive fluid is 105 substantially continuously admitted and exhausted for producing continuous motion of the motor.

This application discloses improvements of the inventions disclosed in my pending 110 applications Serial No. 437,664, filed January 17, 1921, Serial No. 421,748, filed November 4, 1920, and Serial No. 76410, filed December 19, 1925, the last mentioned being a division of said application Serial No. 421,748.

Although I have described one specific embodiment of my invention for purposes of illustration, it is to be understood that wide deviations from the same may be made 120 without departing from the spirit of my invention.

Claims:

1. A drilling machine having, in combination, fluid pressure operated motor means 125 for actuating a drilling tool, said motor means of the type wherein motive fluid is substantially continuously admitted and exhausted for producing continuous motion of the motor, means forming a compressor, 130

a motive fluid supply connection, means for supplying said compressor with live motive fluid and for interrupting said supply on the compression stroke of said compressor while supplying the compressed motive fluid to said fluid pressure actuated motor means.

2. A drilling machine having, in combination, fluid pressure operated motor means for actuating a drilling tool, said motor means of the type wherein motive fluid is substantially continuously admitted and exhausted for producing continuous motion of the motor, means forming a motor operated compressor, a motive fluid supply connection, means for supplying said compressor with live motive fluid for actuation thereof and for supplying the compression chamber of said compressor with live motive fluid whereby the latter is compressed, and means permitting the escape of said compressed live motive fluid from said chamber substantially solely by way of said motor.

3. In a drilling machine, a fluid pressure operated motor for actuating a drilling tool, said motor of the type wherein motive fluid is substantially continuously admitted and exhausted for producing continuous motion of said motor, means providing a motor operated single acting compressor comprising a compressor cylinder and piston, a motive fluid supply connection, conduit means supplying said compressor with motive fluid from said connection for actuation of said compressor, conduit means supplying said motor with motive fluid from said connection by way of said compressor cylinder whereby said motor is operated and said cylinder charged with live motive fluid on the expansion stroke of said compressor, and means acting substantially completely to interrupt communication between said cylinder and connection on the compression stroke of said compressor whereby said motor is then supplied with compressed live fluid.

4. In a drilling machine, a fluid operated motor for actuating a drilling tool, a hammer independent of said motor for actuating said tool, a cylinder for said hammer which with said hammer forms an expandible chamber, an inlet to said expandible chamber having a check valve for automatically permitting flow of fluid to said chamber and preventing flow therefrom, and an outlet from said chamber for conducting actuating fluid to said motor.

5. In a drilling machine, fluid operated percussive means for actuating a drilling tool, means for substantially completely trapping live motive fluid and for causing said fluid to be compressed by energy imparted by said percussive means, fluid operated motor means for actuating said tool

other than said percussive means, said motor means of the type wherein motive fluid is substantially continuously admitted and exhausted for producing continuous motion of the motor, and means for supplying the last mentioned motor means with such compressed fluid.

6. In a drilling machine, a fluid operated percussive means for actuating a drilling tool, a motive fluid supply connection, means for taking a charge of live motive fluid from said connection and for compressing it by energy imparted by said percussive means while preventing return of said charge to said connection, fluid operated motor means for actuating said tool other than said percussive means, said motor means of the type wherein motive fluid is substantially continuously admitted and exhausted for producing continuous motion of the motor, and conduit means for supplying the compressed charge to said fluid operated motor means.

7. In a drilling machine, a fluid operated percussive means for actuating a drilling tool, a motive fluid supply connection, means for taking a charge of live motive fluid from said connection and for compressing it by energy imparted by said percussive means while preventing return of said charge to said connection, a motor for giving angular movement to said tool, and conduit means for supplying the compressed charge to said motor.

8. In a drilling machine, a fluid operated percussive means for actuating a drilling tool, a motive fluid supply connection, means for taking a charge of live motive fluid from said connection and for compressing it by energy imparted by said percussive means while preventing return of said charge to said connection, a rotary engine for rotating said tool, and conduit means for supplying the compressed charge to said engine.

9. In a drilling machine, a hammer piston for actuating a drilling tool, said piston having a pressure surface, a hammer cylinder having a surface opposed to said pressure surface of said piston, a motor for giving angular movement to said tool, conduit means connecting the space between said surfaces to said motor, a motive fluid supply connection, a conduit connecting said connection with the space between said surfaces, a pressure actuated valve for controlling the flow of motive fluid through said conduit effective to cause motive fluid materially to be compressed between said surfaces, and means for causing said piston to reciprocate.

10. In a drilling machine, a hammer piston having a pressure surface, a hammer cylinder having a pressure surface opposed to said pressure surface of said piston, a

motor for giving angular movement to said tool, means constantly supplying said motor with motive fluid, said means intermittently completely trapping and compressing said motive fluid between said pressure surfaces.

11. In a drilling machine, a motor for rotating a drilling tool, a motive fluid supply connection, conduit means connecting said connection to the atmosphere by way of said motor, a check valve for preventing flow through said conduit means toward said connection, and means for trapping and compressing live fluid from said connection between said check valve and motor and supplying the compressed fluid to said motor.

12. In a drilling machine, a hammer for actuating a drilling tool, said hammer having a head and a shank, a motive fluid supply connection, means for intermittently admitting fluid from said connection to said cylinder behind said head for moving said hammer in one direction, a conduit means for supplying motive fluid from said connection to the end of said cylinder fitting said shank, a motor for actuating said drilling tool having an intake in communication with said conduit means, and a valve between said intake and connection preventing flow through said conduit from said cylinder to said connection.

13. In a drilling machine, a cylinder having a larger forward bore and a smaller rearward bore, a hammer piston for actuating a drilling tool, said hammer having a head fitting said larger bore and a shank fitting said rearward bore, a motor for rotating said tool, a motive fluid supply connection, a conduit means connecting said connection to the rearward end portion of the rearward bore and to the intake of said motor, a check valve for preventing flow from said bore to said connection, and means controlled by said shank for admitting fluid from said source alternately to opposite sides of said head.

14. In a drilling machine, a drilling tool, a hammer piston for operating said tool having an intermittently acting pressure surface and a smaller opposed pressure surface, a motor for rotating said tool, and means including a cylinder for said piston and cooperating ports and passages for causing said smaller surface completely to trap and compress live pressure fluid in said cylinder and to supply it to said motor for actuation thereof.

15. In a drilling machine, a drilling tool, a motive fluid supply connection, a hammer piston having an intermittently acting pressure surface, a shank having a smaller opposed pressure surface, said shank for controlling the admission of pressure fluid from said source to said intermittently acting pressure surface, a motor for rotating said tool and having an intake in communication

with the space behind said opposed surface, and means for connecting such space to said supply connection only during the stroke of said piston in one direction.

16. In a percussive tool, a cylinder, a differential piston therein having a continuous pressure surface, a source of motive fluid supply, a passage establishing communication between said source and the cylinder chamber for said continuous pressure surface, said passage being in continuous communication with said source when said tool is in operation, and an inwardly opening check valve controlling said passage.

17. In a percussive tool, a cylinder, a differential piston therein having a rearwardly facing continuous pressure surface, a source of motive fluid supply, a passage establishing communication between said source and the cylinder chamber for said continuous pressure surface, said passage being in continuous communication with said source when said tool is in operation, and an inwardly opening check valve controlling said passage.

18. In a percussive tool, a piston having a head and a rearward shank, a cylinder having portions receiving said head and shank, a source of motive fluid, a passage having an inwardly opening check valve connecting said source with the cylinder chamber rearwardly of said shank, and passages controlled by said shank for alternately admitting motive fluid to the cylinder chambers on opposite sides of said head.

19. In a percussive tool, a piston providing a head and a rearward shank having a portion of reduced diameter, a cylinder having portions receiving said head and shank, a motive fluid supply passage having a port opening into the forward end of the cylinder portion receiving said shank, a motive fluid supply passage having a port opening into said last named cylinder portion rearwardly of said last named port, a fluid operated valve for preventing return flow through said last named passage, a motive fluid supply port opening into said last named cylinder portion intermediate the other ports, a passage connecting an intermediate portion of the cylinder portion receiving said shank with the forward end of the cylinder portion receiving said head, whereby said shank may admit fluid to act on the rearward end of said head during the forward stroke and the rearward end of said shank may admit fluid to act on the forward end of said head during the rearward stroke.

20. In a percussive tool, a piston having a head and a rearward shank, a cylinder having portions receiving said head and shank, a source of motive fluid, a passage connecting said source with the cylinder chamber rearwardly of said shank, a fluid operated valve preventing return flow

90

through said passage, and passages controlled by said shank for alternately admitting motive fluid to the cylinder chambers on opposite sides of said head.

21. A rock drill having, in combination, a rotary chuck formed for carrying a drill steel, a fluid operated hammer for imparting percussion to said steel, a fluid operated motor for rotating said chuck, power transmission means between said motor and chuck, means for varying the mechanical advantage of said transmission, fluid operated mechanism for controlling said means, and means for supplying motive fluid from a source of supply to the recited fluid operated instrumentalities including means for controlling the motive fluid supplied to each whereby the torque impressed on the drill steel may be coordinated with the percussion imparted thereto.

22. A rock drill having, in combination, a rotary chuck formed for carrying a drill steel, a fluid operated hammer for imparting percussion to said steel, a fluid operated motor for rotating said chuck, variable speed reduction gearing for imparting the effort of said motor to said chuck; a casing carrying said chuck, motor and reduction gearing, said gearing comprising a pair of annular gears surrounding the axial line of said chuck and arranged to mesh with a gear coaxial with and operatively connected to said chuck, and fluid operated mechanism carried by said casing for causing one or the other of said annular gears to mesh with said gear operatively connected to said chuck.

23. A rock drill having, in combination, percussive means for a drill steel, a chuck formed for carrying said drill steel, a casing in which said chuck is rotatably mounted, a motor for rotating said chuck, power transmission means between said motor and chuck including a change speed shift gearing, and means for coordinating the torque impressed on the drill steel with the percussion imparted thereto including fluid operated mechanism for actuating said shift gearing.

24. A rock drill having, in combination, a chuck formed for carrying a drill steel, a motor for rotating said chuck, means for rendering said motor operative or inoperative at will to drive said chuck, said means comprising an annular gear surrounding and meshing with a gear on said chuck and

mechanism for selectively placing said gears into and out of mesh, and fluid operated mechanism for actuating said mechanism.

25. A rock drill having, in combination, a chuck formed for carrying a drill steel, a motor for rotating said chuck, means for rendering said motor operative or inoperative at will to drive said chuck, said means comprising an annular gear surrounding and meshing with a gear on said chuck and mechanism for selectively placing said gears into and out of mesh, and manually operated mechanism for actuating said mechanism.

26. A rock drill having, in combination, a hammer cylinder containing a hammer for imparting percussion to a drill steel, a rotatable chuck formed for carrying said drill steel, a motor for rotating said chuck, power transmission mechanism between said motor and chuck comprising a pair of spaced annular gyratory gears surrounding said chuck and a gear splined to said chuck adapted to mesh with either of said annular gears, and means for varying the mechanical advantage of said transmission for coordinating the torque impressed on the drill steel with the percussion imparted thereto or for rendering said motor inoperative to drive said chuck comprising mechanism for holding said gear on said chuck in mesh with either of said gyratory gears or out of mesh with both of them.

27. A rock drill having, in combination, a hammer cylinder containing a hammer for imparting percussion to a drill steel, a rotatable chuck formed for carrying said drill steel, a motor for rotating said chuck, power transmission mechanism between said motor and chuck comprising three gears each with a different number of teeth, gear shifting means for causing one of said gears to mesh with either of the other of said gears or to be held out of mesh with both of them for coordinating the torque impressed on the drill steel with the percussion imparted thereto or for rendering said motor inoperative to drive said chuck, one of said gears being driven by said motor and surrounding said chuck and being mounted for gyratory movement and another of said gears being mounted on said chuck.

In testimony whereof, I have signed my name to this specification.

GEORGE H. GILMAN.
